(57) **CLAIM**

The ornamental design for control head with electroluminescent panel for a land mobile radio, as shown and described.

DESCRIPTION

FIG. 1 is a top view of a control head with electroluminescent panel for a land mobile radio as shown in a first environment. FIG. 2 is a frontal view of a control head with electroluminescent panel for a land mobile radio as shown in the first environment.

FIG. 3 is a bottom view of a control head with electroluminescent panel for a land mobile radio as shown in the first environment.

FIG. 4 is a right side view of a control head with electroluminescent panel for a land mobile radio as shown in the first environment.

FIG. 5 is a left side view of a control head with electroluminescent panel for a land mobile radio as shown in the first environment.

FIG. 6 is a top right side perspective view of a control head with electroluminescent panel for a land mobile radio as shown in the first environment.

FIG. 7 is a top left side perspective view of a control head with electroluminescent panel for a land mobile radio as shown in the first environment.

FIG. 8 is a top view of a control head with electroluminescent panel for a land mobile radio as shown in a second environment.

FIG. 9 is a frontal view of a control head with electroluminescent panel for a land mobile radio as shown in the second environment.

FIG. 10 is a bottom view of a control head with electroluminescent panel for a land mobile radio as shown in the second environment.

FIG. 11 is a right side view of a control head with electroluminescent panel for a land mobile radio as shown in the second environment.

FIG. 12 is a left side view of a control head with electroluminescent panel for a land mobile radio as shown in the second environment.

FIG. 13 is a top right side perspective view of a control head with electroluminescent panel for a land mobile radio as shown in the second environment; and,

FIG. 14 is a top left side perspective view of a control head with electroluminescent panel for a land mobile radio as shown in the second environment.

For FIGS. 1-14, broken lines are for illustrative purposes only, showing the environment, and form no part of the claimed design.
